UNITED STATES PATENT OFFICE.

CHARLES GERTH, OF RACINE, WISCONSIN, ASSIGNOR TO THE HARTMAN TRUNK CO., OF RACINE, WISCONSIN.

DESIGN FOR A TRAVELING-BAG.

41,393.

Specification for Design.

Patented May 16, 1911.

Application filed March 2, 1911. Serial No. 611,940. Term of patent 3½ years.

To all whom it may concern:

Be it known that I, CHARLES GERTH, residing at Racine, in the county of Racine and State of Wisconsin, have invented a new, original, and ornamental Design for a Traveling-Bag, of which the following is a specification, reference being had to the accompanying drawing, forming part thereof.

The figure is a perspective view of a traveling bag, showing my new design.

I claim:

The ornamental design for a traveling bag, as shown.

CHARLES GERTH.

Witnesses:

MAX BLOCH,

CLINT D. FRAZELL.
